GOLF PUTTER HEAD

Eugene R. Leander, Rockford, Ill., assignor to
Pro Enterprises, Ltd., Rockford, Ill.

Filed Jan. 8, 1973, Ser. No. 321,955

Term of patent 14 years

Int. Cl. D21—02
U.S. Cl. D34—5 GH

FIG. 1 is a perspective view of a golf putter head incorporating my new design.

FIG. 2 is a side elevational view of the putter head.

FIG. 3 is a bottom plan view of the putter head.

FIG. 4 is a top plan view of the putter head.

FIG. 5 is a front elevational view as seen from the right of FIG. 1.

FIG. 6 is a rear elevational view as seen from the left of FIG. 1.

FIG. 7 is a cross-sectional view taken along the line 7—7 of FIG. 4.

I claim:

The ornamental design for a golf putter head, as shown.
